UNITED STATES PATENT OFFICE.

VINCENZO PASCUCCI, OF NEW YORK, N. Y.

SIGNALING DEVICE.

1,259,278.

Specification of Letters Patent. Patented Mar. 12, 1918.

Application filed September 26, 1916. Serial No. 122,185.

To all whom it may concern:

Be it known that I, VINCENZO PASCUCCI, a citizen of the United States, and resident of New York city, in the county of Kings 5 and State of New York, have invented certain new and useful Improvements in Signaling Devices, of which the following is a specification.

My invention relates to signaling devices 10 and especially to horns used on automobiles.

The object of my invention is to provide a simplified construction of the mechanism, whereby the friction of the operating parts is reduced so that the horn will give a 15 longer signal or more sustained tone with a given impulse, and also a construction having less parts and costing less to make.

Referring to the drawings.

Figure 1 is a view of the open end of the 20 housing in which the rotating mechanism is placed, and disclosing the mechanism therein, and drawn to full size as actually made.

Fig. 2 is a longitudinal sectional view taken on line $\alpha-\alpha$ of Fig. 1.

25 "A" indicates the housing which is preferably made of sheet metal, having a flange "A¹" for holding the usual horn and diaphragm which are not shown hereon as they form no part of the present invention.

30 The housing is provided with two threaded openings "A²"—"A³" respectively, oppositely disposed, in which are fitted screws "B"—"B" respectively with lock nuts "C"—"C" respectively, to hold them in adjusted position. The inner ends of screws "B"—"B" are drilled to provide bearings "B¹" for the end of shaft "D." One end of this shaft "D" is relatively of larger diameter and is provided with teeth to form 40 a ratchet gear "E", cut therein and extending to shoulder "D¹" formed at the points where this shaft "D" is enlarged in its diameter.

45 Mounted on this shaft "D" is a disk of metal "F" serving as a fly-wheel and free to rotate on said shaft "D" independent of the rotation thereof, and having a ratchet shaped serrated periphery "F¹" which operates a diagram (not shown) in the usual manner well known in this art, when the fly-wheel is rotated.

50 Mounted on the side of the fly-wheel adjacent to the gear teeth "E" is a pawl "G" and spring "G¹" to hold the pawl in operative relation with the gear teeth "E." A

cotter pin "H" holds the fly-wheel loosely against the shoulder "D¹." A guide rod "I" is fastened at one end to the casing or housing at "A²" and projects toward an opening "A⁴" in the casing, and through this opening extends a push-rod "J", having a rack "J¹" formed thereon which engages the gear teeth "E", and having a cylindrical opening or bore indicated by "J²" into which the guide-rod "I" projects as illustrated. 60 Mounted on the guide-rod is a helical spring "K" which extends the length of the cylindrical bore and serves to force the push-rod "J" to its normal position.

To operate the device the push-rod is 70 forced quickly inward which causes the shaft "D" to turn and rotate the fly-wheel through the instrumentality of pawl "G" which engages the gear "E" and, after the fly-wheel is started, the pawl runs over the 75 teeth, being carried by the wheel, as will be readily understood. The serrated periphery of the wheel, in turn, operates the diaphragm.

By this construction the gear teeth "E" 80 serve both as a ratchet and pinion, thus dispensing with parts heretofore used, also the guide-rod construction is made sufficiently large and strong to dispense with other parts heretofore deemed necessary for 85 such construction.

Having thus described my invention, I claim as new and desire to secure by Patent.

1. In combination, a housing having a shaft mounted therein provided with a gear, 90 a fly-wheel mounted to rotate on said shaft, a pawl carried by said fly-wheel and engaging said gear and a push-rod having a rack which also engages said gear to turn said shaft.

2. In combination, a housing having a shaft mounted therein provided with a gear made integral therewith and having a shoulder located at one end of said gear, a fly-wheel mounted on said shaft and abutting 100 said shoulder; a pawl carried by said fly-wheel and engaging said gear, a push-rod having a rack which also engages said gear to turn said shaft and a cylindrical bore formed therein, a guide-rod extending from 105 the housing into said bore and serving to support said guide-rod in its movement, and a helical spring closely fitting said bore and supported by said guide-rod.

3. In combination, a housing having a 110

shaft mounted therein provided with a gear, a fly-wheel rotatably mounted on said shaft, a push rod mounted to one side of the said fly wheel and having a rack integral therewith adapted to engage said gear, and a pawl mounted on the same side of said fly wheel and in engagement with said gear.

Signed at New York, in the county of New York and State of New York, this 21st day of September, A. D. 1916.

VINCENZO PASCUCCI.
